APPARATUS, INCLUDING AN AIR TRAP FOR
UNLOADING LIQUID FROM TANK CARSAlbert L. Hickerson, Bartlesville, Okla., assignor
to Phillips Petroleum Company, a corporation
of Delaware

Application June 26, 1944, Serial No. 542,199

2 Claims. (Cl. 222—372)

1

This invention relates to methods of and means for pumping fluids and it has particular relation to the pumping of an inflammable liquid, such as gasoline, in the rapid unloading of large containers, such as railroad tank cars.

In the art of unloading railroad tank cars it has been found inefficient with respect to time to allow the gasoline to merely drain out of the car. It has been found desirable to operate the pump so as to create suction which will quickly pull the gasoline out of the tank car with the aid of atmospheric pressure. Unfortunately, in some instances the pump has been so large and operated at such a high speed that when one or more of the tank cars was emptied the pump has drawn air into itself with the result that the electric motor driving the pump has increased its speed and electric current in the motor windings to such an extent as to catch fire. In some instances the gassing up of the unloading pump has resulted in burning up the motor and pump and even setting the entire loading rack and substantially empty tank cars on fire. When a tank car has just been emptied there is a likelihood that the incoming air will form an explosive mixture inside the tank car; and if this explosive mixture is ignited the result is to make the tank car into a bomb which will wreck the entire neighborhood.

It is necessary, especially in wartime, to obtain the advantages of faster unloading with less labor involved and with the desirable safety feature of preventing the gassing of the unloading pump and any possible fire in the unloading rack installation, and the principal object of my invention is to achieve these advantages so necessary in the rapid handling of aviation gasoline for the armed forces.

Another object of my invention is to provide a suitable method and means for pumping liquids.

Another object is to provide a loading rack for unloading railroad tank cars by rapid pumping in which it is impossible for the pump to become filled with gas so that the pump and pump motor will not run wild and the danger of fire is thereby reduced.

A further object is to provide a recycling bypass from a liquid pump in combination with an air trap so that the pump will pump a liquid at all times.

A further object is to simplify and speed up the unloading of liquids from tank cars by preventing gassing up of the unloading pump.

A still further object is to provide in such a recycling bypass a valve controlled by a float in

2

the air trap so that when the liquid level in the air trap falls dangerously low the recycling bypass will be open to recycle liquid so that the liquid pump will always be full of liquid.

5 Other objects are to provide methods and apparatus economical of material and labor and suitable for commercial competition with existing devices and in which a high safety factor is maintained with respect to possible fire.

10 Numerous other objects and advantages will be apparent to those skilled in the art upon reading the accompanying specification and claims and studying the accompanying drawing.

In the drawings:

15 The single figure of the drawings is an elevational view with a portion of the ground in cross section, showing an unloading rack for railroad tank cars embodying the present invention.

In the drawing a tank car 1 is one of a series 20 of tank cars placed on railroad siding 2 for the purpose of being unloaded in a rapid manner by an unloading rack generally designated as 3.

25 Each tank car 1 is normally provided with an upper valve 4 communicating with the atmosphere and with the interior of the tank and with a belly valve 5 for controlling flow of liquid from the bottom of the tank. This invention may obviously be applied to other valve arrangements and other types of tank cars without invention.

30 Unloading rack 3 may be comprised of a header 6 running parallel to the railroad siding 2. The header 6 may have a number of feed lines 7 connected thereto and spaced approximately the length of a tank car apart. A control valve 8 is provided in each feed line 7. The invention is of course also useful for only one car 1 and one feed line 7, so the number of feed lines is not critical at all.

35 Feed line 7 is provided with a flexible connection 9, which allows some flexibility in connecting the line 7 to the belly valve 5, which connection is made by any suitable means. Each feed line 7 is connected normally to the respective tank car 1 which is placed opposite it. Feed line 7 40 may be a flexible synthetic rubber hose, or may be metal with a telescopic section therein (not shown) to allow for differences in tank car construction and some range as to how they are spotted on the siding by the train crew. Such feed lines are old and any of these old feed lines 45 may be used.

50 The unloading rack 3 has a main line 11 leading from header 6 to an air trap 12. Air trap 12 has a drain valve 13 which generally remains closed. Air trap 12 has an inverted U tube 14

which rises above the highest possible level of liquid in any of the tank cars 1 and then leads to a control valve 18 located at a convenient height for operation by the man on the job. Valve 18 opens or closes the top of the air trap 12 to the atmosphere. From the lower portion of air trap 12 a line 16 runs to a liquid pump 17. Any type of pump may be employed and pump 17 is driven by any type of motor (not shown). Valve 18 controls the flow of liquid through pipe 16.

Pump 17 discharges through discharge line 19, and discharge line 19 may lead to suitable tanks or other tank vehicles, such as automobile tank trucks (not shown). Discharge line 19 has a control valve 21 therein and a check valve 22 permitting flow of fluids therethrough to the right of the drawing but preventing flow in the reverse direction.

Between pump 17 and check valve 22 line 19 is provided with a recycling bypass 23. The recycling bypass may be provided with valves 24 and 25 for manually shutting off flow therethrough, but like valve 18, neither of the valves 24 or 25 is essential to the operation of the invention but each is convenient at times in the removal of parts, repair, or replacement.

Recycling bypass 23 is provided with a control valve 26 which closes bypass 23 whenever the liquid level in air trap 12 is above level 27. The operation of the valve 26 to accomplish this purpose is made possible by float chamber 28 and pipes 29 and 31 connecting the float chamber with the interior of air trap 12 above and below level 27. The usual float (not shown) is provided in chamber 28, and this float operates valve 26 as set forth by any suitable linkage old in the art.

The liquid is at level 32 at the particular moment of unloading depicted in the drawing.

Operation

The tank cars 1 to be unloaded are spotted on the siding 2 so that their belly valves 5 are opposite the feeder lines 7 and the lines 7 are coupled to their respective valves 5. At this time all of the valves are closed. The operator opens valves 4, 5, 8 and 15 and the liquid from car 1 will then fill air trap 12 and car 1 and the intermediate pipes 7, 6 and 11 up to the level 32. The operator then closes valve 15, and of course, the liquid in 12 being above level 27 has automatically closed valve 26.

The operator then opens valves 18, 21, 24 and 25 and starts the motor of pump 17.

The closed air trap 12 will now permit the unloading pump 17 to pull down a considerable vacuum in the top of trap 12; pump 17 creates suction, lowering the liquid level in trap 12 and the suction in combination with the pressure of the atmosphere entering tank 1 through valve 4 acts to force the liquid out of tank 1 in a very much shorter time than would be possible by other means or methods, such as merely draining car 1 by gravity. Pump 17, being of very high capacity, unloads the cars 1 in a most rapid manner, but as the cars become unloaded completely, and one car usually becomes unloaded before the others, air will be drawn into the system and this air will cause trouble in systems not employing the present invention.

When one of the tank cars becomes empty air will pass through its valve 4 and down one of feed lines 7 into header 6 and into air trap 12 lowering the liquid level in 12. If this liquid level were allowed to drop enough so that air would be

drawn in line 16 this air would get in pump 17 and the pump would run wild as there would be no load on pump 17 or the motor driving the pump. The result of this might be enough mechanical and electrical overheating of the pump motor to set the loading rack on fire. Parts containing explosive mixtures of gasoline might blow up in dangerous fragments, and the fire would destroy the tank cars and other equipment depending on whether it was possible to control the fire or not.

In the present invention this filling of pump 17 with air is not permitted, because when the level of liquid in trap 12 falls below line 27 the float in casing 28, which is floating on liquid supplied through line 31, opens valve 26 by means of suitable linkage (not shown). These float controlled valves are old in the art and any suitable one of these old valves may be used.

When valve 26 is open, liquid being pumped by pump 17 is immediately bypassed through recycling bypass 23 and enough liquid pours into trap 12 to keep the end of pipe 16 under liquid at all times, even when all the tank cars 1 are empty, so that pump 17 will always have sufficient load thereon so that the motor driving pump 17 will not get hot and catch fire, or the pump be injured by high speed.

The air which finally will enter the header 6 and air trap 12 will finally release the vacuum, and when the tank cars are all nearly empty and the net positive suction head is low, the unloading pump 17 will deliver liquid faster through pipe 19 than the liquid will gravitate into the air trap 12 but gassing up of the pump is prevented by the liquid level float control 28 opening valve 26, which is preferably a motor valve, and thus bypassing liquid from the pump discharge pipe 19 to maintain the liquid level at level 27 in the air trap so that the pump 17 always has a proper load. When the tank cars are empty the motor of pump 17 is cut off, all the valves are closed and pipes 1 are disconnected at 9 and 5 and tank cars 1 removed from siding 2.

Obviously while the method and apparatus of the invention are shown in the important situation where railroad tank cars are unloaded, the source of liquid need not be a railroad tank car 1, but may be any source, either of a vehicular or non-vehicular nature, and pipe 19 may discharge to any type receiver. The type of motor or turbine driving pump 17 is not critical as any type pump and driver may be injured by running wild.

It is believed obvious, therefore, that I have devised a method and apparatus suitable for carrying out the objects of the invention, and that minor changes and modifications may be made by those skilled in the art without departing from the spirit of my invention, the scope of which is defined by the following claims.

Having described my invention, I claim:

1. An apparatus for unloading a tank car containing a liquid, which comprises an elongated upright air-trap extending from a point at least as high as the level of the top of said tank car to a level well below the bottom of said tank car; a conduit joining the bottom of said tank car and the bottom portion of said air-trap; a discharge conduit leading from the bottom portion of said air-trap; a pump in said discharge conduit; a by-pass conduit leading from said discharge conduit downstream from said pump to the lower portion of said air-trap at a point below the level of the bottom of said tank car; a valve in said by-pass; a liquid-level responsive means operatively con-

nected with said air-trap on a level with the bottom of said tank car; and operative means joining said liquid-level responsive means and said by-pass valve to open said by-pass valve when the liquid level in said air-trap falls to said level.

2. In a system for removing liquid from a liquid supply source the combination which comprises, an elongated upright air-trap extending from a level above the top of said liquid supply source to a level below the bottom of said liquid supply source; a liquid conduit connecting the bottom of said liquid supply source with the bottom portion of said air-trap; a valve for closing the upper end of said air-trap; a liquid discharge conduit leading from the bottom portion of said air-trap; a discharge pump in said discharge conduit; a by-pass line connecting the discharge side of said pump to the lower portion of said air-trap; a liquid level control connected to said air-trap on a level with the bottom of said liquid supply source; and a valve in said by-pass conduit

operatively connected to said liquid level control so as to be closed when the liquid level in said air-trap is above said liquid level control.
